The ornamental design for a pair of sunglasses lens covers, as shown and described.

DESCRIPTION

FIG. 1 is a perspective view of a pair of sunglasses lens covers showing my new design being applied to the left lens of a pair of sunglasses;

FIG. 2 is a front view of the pair of sunglasses lens covers of FIG. 1 shown in an applied condition;

FIG. 3 is a top view of the pair of sunglasses lens covers of FIG. 1;

FIG. 4 is a bottom view of the pair of sunglasses lens covers of FIG. 1;

FIG. 5 is a left side view of a single lens of the pair of sunglasses lens covers of FIG. 1; and,

FIG. 6 is a right side view of a single lens of the pair of sunglasses lens covers of FIG. 1.

The broken lines shown in FIGS. 1-6 represent the portions of the design which form no part of the claim.
